Louis Pagger.

UNITED STATES PATENT OFFICE.

PETER CHRISTIAN EMMERIK ULDALL, OF COPENHAGEN, DENMARK.

MANUFACTURE OF HAY AND MANURE FORKS.

SPECIFICATION forming part of Letters Patent No. 364,614, dated June 7, 1887.

Application filed January 22, 1887. Serial No. 225,095. (No model.)

To all whom it may concern:

Be it known that I, PETER CHRISTIAN EMMERIK ULDALL, a subject of the King of Denmark, residing at Copenhagen, in the Kingdom of Denmark, have invented certain new and useful Improvements in Apparatus for and Method of Forming Forks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 Figure 1 is a plan view of the blank for my improved hollow fork. Figs. 2 and 2^a show, respectively, in plan view and in side view a partly-finished fork resting in the lower intaglio die. Fig. 3 is a transverse sectional view of the upper and lower dies and of the blank. Fig. 4 is a similar view showing the blank in a die giving a still further folding to the blank. Fig. 5 is a similar view showing the edges of the blank brought together. Fig. 6 is a plan view 25 of a die for giving the prongs or tines of the fork their proper lateral curve, and Fig. 7 is a longitudinal vertical sectional view of a die giving the final curve to the prongs or tines of the fork.

30 Similar letters of reference indicate corresponding parts in all the figures.

My invention has relation to forks used for agricultural purposes, such as hay and dung forks; and it consists, first, in the improved method of and apparatus for manufacturing hollow-pronged forks, and, second, in the improved construction of the hollow-pronged fork produced by the method as hereinafter more fully described and claimed.

35 In the accompanying drawings, the letter *a* indicates the portion of the blank which is intended for the socket of the fork for the insertion of the handle, and *b*' and *b*^a indicate the portions of the blank forming the tines or prongs.

40 This blank, which for a two-pronged fork is of substantially the same shape as shown in Fig. 1, is placed in an intaglio die, *A*', having a small concavity in its face corresponding in shape to the general outline of the blank, and 45 a plunger or die in relief, *A*^a, is forced down

upon the blank, as shown in Figs. 3 and 4, the dies first used having less of an indentation and raised portion, respectively, than the dies used afterward, the dies gradually bringing the edges of the blank to curve upward and 55 toward each other, as shown in Fig. 4. The blank is thereupon placed between two dies, *B*' and *B*^a, the lower one of which is formed with a shallow recess or indentation corresponding in shape to the form of the pressed 60 blank, and the upper die is formed with a recess, *C*, having inclined or beveled sides and a flat bottom, as shown in Fig. 5, the branches of the said recess gradually tapering toward their points, and the inclined sides of the recess will serve to close the edges of the blank and give the pressed and nearly-finished blank the proper shape. The blank is now heated 65 and the edges, which are pressed close together by the last process, are welded together, whereupon the blank is placed into a die or former formed by two parts, *D*' and *D*^a, which inclose the socket and the outer sides of the prongs, when a plunger, *D*^a, of a blunt and rounded wedge shape is inserted between the prongs, 70 spreading them and giving them the proper lateral curve.

It now remains to give the prongs the proper curve transverse to the plane through the socket and prongs, and this is accomplished 75 by placing the blank between two dies, *E*' and *E*^a, respectively formed in their faces with a recess corresponding to the shape of the fork, and having, respectively, a concave and a convex curved face, so that the upper portions of 80 the prongs may be curved into a plane below the plane between the points of the prongs and the socket. The fork is now so far finished that all which remains is to temper it and to 85 sharpen and finish the fork for market, and it will be seen that a very light article is obtained on account of the prongs being hollow, while the prongs will be equally as strong as solid prongs and possess comparatively greater elasticity and yielding power than the solid 90 and heavier prongs.

When forks with more than two prongs are manufactured, the dies will of course have their respective recesses and raised parts formed to correspond to the shape of the many-pronged 95 100

blank, and the plunger in the die giving the lateral spread to the prongs will be divided into a number of parts, each corresponding to the space between two prongs, the entire operation and method of manufacture being the same as with the two-pronged fork, the only difference being the difference in the shape of the dies.

The dies are here shown flat, one die being forced down upon the other; but it follows that the dies may be formed upon rollers between which the blanks may be fed, in the same manner as a number of other metallic objects are cut or formed from rough blanks inserted between roller-dies—as, for instance, links and similar objects.

Numerous other modifications may be made in the construction of the several parts of the dies and other machinery for manufacturing the forks without departing from the spirit of my invention, which changes all may suggest themselves during the manufacture of the implements.

Having thus described my invention, I claim and desire to secure by Letters Patent of the United States—

1. The improved method of manufacturing hollow-pronged forks, consisting in gradually curving the edges of a flat fork-shaped blank between dies, uniting the edges by welding, and then giving the fork the desired lateral and transverse curve of the prongs, as and for the purpose shown and set forth.

2. The improved apparatus for manufacturing hollow-pronged forks, consisting of intaglio and relief dies, a blunt and rounded wedge-shaped plunger, a forked die, and two dies having, respectively, a convex and a concave face, as and for the purpose shown and set forth.

3. In an apparatus for manufacturing hollow-pronged forks, the combination of a fork-shaped die having prong-receiving grooves or recesses in the inner sides of its branches and a blunt rounded wedge-shaped plunger having grooves in its sides, as and for the purpose shown and set forth.

4. In an apparatus for manufacturing hollow-pronged forks, the combination of two dies, one of which has a shallow recess, and the other one has a recess the sides of which are beveled or inclined toward each other and having a flat bottom, as and for the purpose shown and set forth.

5. As an improved article of manufacture, a fork having tubular or hollow welded and swaged prongs, as and for the purpose shown and set forth.

In testimony whereof I affix my signature in presence of two witnesses.

PETER CHRISTIAN EMMERIK ULDALL.
